UNITED STATES PATENT OFFICE.

CHARLES S. BURTON, OF OAK PARK, ILLINOIS, ASSIGNOR TO STEWART-WARNER SPEEDOMETER CORPORATION, OF CHICAGO, ILLINOIS, A CORPORATION OF VIRGINIA.

PRESSURE FEED FOR SUPPLYING FUEL TO INTERNAL-COMBUSTION ENGINES.

Application filed March 2, 1923. Serial No. 622,272.

To all whom it may concern:

Be it known that I, CHARLES S. BURTON, a citizen of the United States, residing in the village of Oak Park, in the county of Cook and the State of Illinois, have invented certain new and useful Improvements in Pressure Feed for Supplying Fuel to Internal-Combustion Engines, of which the following is a specification, reference being had to the accompanying drawings, forming a part thereof.

The purpose of this invention is to provide means for furnishing fuel to the carburetor of an internal combustion engine particularly of an automobile or other motor vehicle, from a main reservoir situated at a lower level than the carburetor intake, by gas pressure exerted on the fuel at the space from which it is to be lifted. It consists in the elements and features of construction shown and described as indicated in the claims.

In the drawings:—

Figure 1 is a diagrammatic view of the nature of a side elevation of a portion of an automobile and its engine equipped with fuel feeding device embodying this invention.

Figure 2 is a vertical section of the main fuel tank at a plane axial with respect to the fuel lifting device therein which embodies this invention.

Figure 3 is a section at the line 3—3 on Figure 2.

Figure 4 is a section at the line 4—4 on Figure 2.

Figure 5 is a section at the line 5—5 on Figure 2.

Figure 6 is a plan view of a closure plate for the hanger which carries the pressure chamber.

Figure 7 is a vertical axial section of the portion of the pressure pipe line and appurtenances which appears in Figure 1 extending above the engine.

Figure 8 is a vertical axial section of the part of the fuel delivery pipe line and stand pipe thereon which appears in Fig. 1 forward of the dash.

In the structure shown in the drawings B represents the engine from one of whose cylinders as indicated by the nipple connection, B¹, gas pressure is derived and conducted through a pressure pipe line, 35, to

a pressure chamber, 1, situated and connected for being filled with fuel by gravity from the main fuel reservoir or tank, A, said pressure chamber being preferably, as shown, mounted within the main tank, A, being suspended by means of a tubular hanger, 28, from the margin of an aperture, a, in the top of the tank, A, as more particularly hereinafter described, and having its intake for liquid fuel through its bottom cap, 2, positioned near the bottom of the main tank, A, and having its intake port, 2^a, controlled by a downwardly seating check valve, 3, retained in proper proximity to its seat, K¹. The pressure chamber, 1, is desirably dimensioned to contain somewhat more than enough liquid fuel to fill the fuel delivery pipe line, 34, and a stand pipe, 33, thereon and the carburetor float bowl, C; the excess capacity of said pressure chamber above the capacity of said pipe line, stand pipe and flow bowl being desirable for a function or feature of operation of the device hereinafter explained.

The chamber, 1, is closed at the top by a closure casting, 5, whose margin lodges on the upper end of the tube which constitutes the body of the pressure chamber, 1, and which is clamped liquid-tight thereon by an annular coupling, 26, which is screwed onto the upper end of the tubular body, 1, having the interiorly projecting annular flange, 26^a, for engaging the margin of the closure casting, 5. Said coupling, 26, has also an upwardly projecting annular flange, 27, exteriorly threaded for having screwed onto it the lower end of the tubular hanger, 28. This hanger, though for convenience tubular, does not constitute a chamber being laterally slotted as seen at 29 for nearly its whole length rendering it a skeleton. Its upper end is closed by a circular plate, 28^a, which is clamped onto the upper end of the tubular hanger by a flange plate, 30, which is dimensioned forlapping and being bolted onto the margin of the aperture, a, in the main tank, A, and which has a downwardly projecting annular flange, 30^a, interiorly threaded for screwing onto the upper threaded end of the tubular hanger, 28, and an interiorly projecting annular flange, 30^b, for engaging and clamping the plate, 28^a.

A final section, 35^a, of the pressure pipe line, 35, extends down through a suitable

aperture, 32, in the plate, 28^a, and is screwed gas and liquid tight into the casting, 5, into the top closure for the pressure chamber, 1. This casting, 5, has a boss, 5^a, 5 projecting from its lower side for convenience of forming therein certain passages for atmosphere vent, pressure excess and relief, and fuel discharge, as will now be described.

10 From the upper side of the closure casting, 5, there is bored a valve chamber, 8, which is closed at the top by a plug, 6, having a small axial air vent port, 7, into which desirably but not indispensably there may be 15 screwed a slender vent pipe, 7^a, which extends up in the main tank, A, to a point above the high liquid level thereof, and which may extend out through the plate, 28, as shown. A bore is made at 11 along 20 side the valve chamber, 8, and extending to a point below the level of the bottom of that chamber. This bore is connected by a cross-bore, 10, bored in from the left hand end of the boss, 5^a, and closed at its outer end 25 by a plug, 12, and into this cross bore a vertical bore, 13, is made at the center of the bottom of the valve chamber, 8, aligned therefore with the air vent, 7; a lateral entrance to the valve chamber, 8, is bored in 30 from the left hand end of the boss, 5^a, as seen at 8^a. A disk valve, 9, is placed in the valve chamber, 8, before inserting the plug, 6, said valve having desirably a slender wire stem, 9^a, extending down through the 35 free guide aperture in the bottom of the valve chamber; and a cork float, 9^c, is placed in the chamber, 1, and checked between vertical guide wires, 9^d, which extend down from the closure casting, 5, whereby the 40 float is retained in a vertical path in which it encounters the end of the valve stem, 9^a, when the liquid rises to a predetermined height in the chamber, 1. Upon considering this construction it will be understood 45 that in the absence of pressure through the pressure pipe line the chamber, 1, will be filled by gravity flow past the check valve, 3, free atmospheric vent being obtained through the vent port, 7; and it will also 50 be understood that upon the pressure arriving through the pressure pipe line, and the liquid level having risen in the chamber, 1, to the predetermined limit for causing the float, 9^c, to lift the valve, 9, to its seat, said 55 valve, 9, will be held by the gas pressure seated against the lower end of the plug, 6, closing the atmosphere vent, 7.

The closure casting, 5, is also bored from its upper side to form a valve chamber, 14, 60 into which the fuel uptake pipe, 15, is screwed from below, said pipe extending down in the pressure chamber, 1, and opening for fuel intake near the bottom of that chamber. A ball check valve, 16, seats downwardly at the bore, 18, into which the up-

take pipe, 15, is connected; and a bushing, 17, screwed into the upper end of the bore which forms the valve chamber, 14, has screwed through it the initial member, 34^a, of the fuel delivery pipe line, 34, the lower 70 end of said initial member, 34^a, projecting into the valve chamber, 14, stopping the check valve, 16, in its movement away from its seat, the end of said pipe, 34^a, being slotted and notched as shown at 20 for free 75 access of the liquid to said pipe around the check valve. From the port, 18, below the seat of the check valve, 16, a pressure relief duct, 22, is bored in from the right hand end of the boss, 5^a, its outer end being closed 80 by a plug, 23, and this relief duct is continued upward by a bore, 21, into whose upper end there is screwed the pressure relief pipe, 24, which extends up in the main tank 85 preferably to a point above the high liquid level thereof.

Referring now to the pressure connection with the cylinder of the engine selected for furnishing the pressure; it will be noted that a check valve, 40, is provided seating back 90 toward the cylinder port for retaining the pressure in the pressure pipe line in the intervals between pressure impulses derived from the cylinder; and at any convenient point in the pipe line beyond this check 95 valve there is desirably placed a cushioning and pressure maintaining chamber, 41, and beyond this chamber a restricting plug, 42, is introduced in the pipe line to restrict the flow of the gas delivered under the high 100 pressure from the engine cylinder, so that pressure will accumulate relatively slowly in the pressure chamber, 1, but without interruption or material variation; the intermittent pressure furnished by the engine 105 cylinder being converted into continuous pressure by the cushioning and pressure-maintaining chamber, 41, located under the pipe line as described.

Desirably the fuel delivery pipe line, 34, 110 has a T-fitting interposed a short distance back of its connection with the carburetor float bowl, most conveniently at a point immediately forward of the dash as seen in Figure 1, and into the upwardly projecting 115 stem of this T-fitting there is screwed a stand pipe, 33, which may extend to any convenient height in front of the dash. Onto the upper end of this stand pipe there is screwed a cap, 36, having a vent port, 37; 120 and within the cap there is placed a cork, 38, of diameter to move freely in the cap with some liquid clearance around it and adapted thereby to be floated up against the top of the cap and act as a valve to close the 125 vent port, 38, if the stand pipe should at any time become filled with liquid.

Upon considering the structure above described it will be understood that the main tank, A, being supplied with gasoline and 130

the engine at rest the pressure chamber, 1, will be filled by gravity flow from the tank; and that upon the engine being started by the starter or being turned over by the crank, 5 gas pressure will be transmitted through the pressure pipe line to the chamber, 1, and will force down the liquid in that chamber forcing it up into the fuel delivery line filling that line and the carburetor float 10 bowl and the stand pipe, 33, by the time the level in the pressure chamber has been forced down to the intake of the uptake pipe, 15; whereupon the pressure gas will drive up that pipe, in part driving the liquid before 15 it and in part driving through the liquid, and will find vent through the pressure vent pipe, 24; whereupon the liquid which has been forced out and up the fuel delivery pipe before the vent occurred being retained 20 against returning by the check valve, 16, the chamber, 1, will be refilled by gravity the float under the head of liquid in the main tank, the chamber, 1, being vented through the air vent, 7. The pressure gas which is 25 continuing to flow in through the pressure line while the liquid is rising in the chamber, 1, will be mainly vented through the atmosphere vent, 7, until the liquid rises so far as to cause the float 9^c, to lift the valve, 30 9, to its seat, whereupon the pressure jet will hold that valve seated, closing the vent, 7; and thereafter the gas pressure will accumulate more rapidly in the chamber, 1, and drive out the liquid through the uptake pipe, 35 15, into the pressure supply line as before reviewing the former cycle of operations. The fuel in the stand pipe, 33, will supply the requirements of the carburetor during the interval of refilling the chamber, 1, and 40 the discharge from the chamber, 1, will be delayed as to its completion until the consumption of fuel by the engine makes room for the final delivery which will permit the chamber, 1, to vent through the pipe, 24, 45 and be ready for refilling. The purpose of making the capacity of the chamber, 1, great enough to fill the delivery pipe line, the carburetor, float bowl, or stand pipe, 33, is to adapt the device to operate as a primer. It 50 may be preferred to make the chamber, 1, of less capacity than necessary for this purpose. And said chamber, 1, may be made only of sufficient capacity to meet the maximum requirements of the engine during the 55 filling of the chamber, 1, thus avoiding the delayed emptying and refilling of that chamber, 1, except to the extent that the engine requirements at any time are less than maximum. And the capacity of the stand pipe, 60 33, may be sufficient to cover the variation from minimum to maximum requirements of the engine; whereby the stand pipe will never fill so as to bring the cork, 38, into service as a valve for closing the vent to 65 prevent overflow.

It may be found desirable to limit the pressure which can be accumulated in the pressure maintaining chamber, 41, by providing a spring-pressed vent valve, 43, for this chamber and providing the spring, 43^a, 70 which holds the valve seated with a tensioning screw, 44, for adjusting it to any desired limit of pressure in the chamber.

It will be noticed that while the pressure is lowering the level in the chamber, 1, before it is lowered to the level of the intake mouth of the pipe, 15, by which pressure is fed through said pipe, 15, and the vent pipe, 24, liquid will be driven out through said vent pipe, 24, simultaneously with the delivery of liquid up through the pipe, 34^a, and the remainder of the fuel delivery line to the carburetor. This movement of the liquid which is delivered back from the chamber, 15, into the main tank from which it originally came is functionless in so far as that the mere transference of the liquid from one chamber to the other has no purpose. But the intended function of the construction is that when the tube, 24, is occupied 85 by liquid, the liquid has the function of an obstructing valve restricting the discharge through said tube, both by the inertia of the liquid and the friction of the liquid on the enclosing tube; but when the liquid is finally 90 driven out by the pressure because the tube affords substantially free vent for the gas, and it is considered preferable to thus move a certain quantity of liquid back and forth between the two chambers without function 95 as to the movement itself, rather than to provide mechanical valve means for preventing the flow of liquid adapted to open to permit the flow of pressure gas at the proper stage in the cycle of operation as described. The described function of the pipe, 24, as to liquid conduit, viz, making the liquid serve as a discharge-restricting valve, 100 may be increased to any desired extent by extending the pipe, 24, as for example, by 110 the coil, 24^a, shown in Figure 2. The extent and dimensions of this pipe, 24, and its extension would be determined in each particular construction, in view of the degree 115 of pressure under which the pressure gas is delivered and the depth of liquid to be maintained as a minimum in the reservoir. In any case, the duct, 24, it will be observed, serves to an extent as an atmosphere vent 120 in the filling process, causing the up-take pipe, 15, and said tube, 24, to fill almost instantaneously to the height of liquid in the reservoir, A, but this does not dispense with the vent provided through the vent port, 7, said vent port being necessary in order to permit 125 the chamber to fill outside of the up-take pipe, 15. On the other hand, the vent port, 7, does not dispense with the vent, 24, because said vent, 7, does not open until the pressure above the liquid in the chamber, 1, 130

has become relieved, which is accomplished through the vent, 24.

I claim:

- 5 1. In a feeding device for internal combustion engines in combination with a fuel reservoir at a lower level than the engine fuel intake; a relatively small pressure chamber positioned and connected for being filled with liquid by gravity from said reservoir; a pipe line to said pressure chamber from a source of gas pressure, a fuel delivery conduit leading from the lower part of said pressure chamber to the engine carburetor and a relatively restricted pressure 10 vent duct leading from the pressure chamber and discharging in the main reservoir, the communication of said vent duct with the pressure chamber being at a selected level down to which the liquid contents of 15 said chamber are to be forced by the gas pressure for delivering said liquid contents from said chamber; and means preventing the return to the pressure chamber of the liquid so delivered therefrom.
- 20 2. In the construction defined in claim 1 foregoing, the source of gas pressure being a cylinder of an engine to be served, whereby the pressure communicated is intermittent; a check valve in the pressure connection seating back toward the engine for retaining the pressure transmitted and preventing suction back toward the engine; a cushioning and pressure-maintaining chamber on the pressure line between the engine and the pressure chamber, the pressure duct having its discharge into the pressure chamber restricted relatively to the pressure vent duct.
- 25 3. In the construction defined in claim 1 foregoing, a stand pipe on the fuel delivery line anterior to its connection with the car-

buretor, said stand pipe having its upper end closed and provided with a restricted air vent aperture, and a float valve in the stand pipe adapted to be floated to its seat closing 45 said vent aperture when the stand pipe is substantially filled with liquid.

4. In the construction defined in claim 1 foregoing, the pressure chamber having a fuel inlet valve at the bottom opening for inflow and seating against outflow from said pressure chamber and the fuel delivery pipe from said pressure chamber comprising an uptake member extended down through the top thereof and opening for fuel intake near the bottom of said chamber; a check valve in said uptake pipe seating against return flow of the fuel to the pressure chamber, the pressure vent duct leading from said uptake pipe at a point below said check valve. 50 55 60

5. In the construction defined in claim 1 foregoing, the source of gas pressure being a cylinder of an engine to be served, whereby the pressure derived is intermittent; a check valve in the pressure connection seating back toward the engine for retaining the pressure transmitted and preventing suction back toward the engine; a cushioning and pressure-maintaining chamber on the pressure line between the engine and the pressure chamber, the pressure duct having its discharge into the pressure chamber restricted relatively to the pressure vent duct, the pressure-maintaining chamber having a spring seated pressure-limiting or safety 70 75 valve, and means for adjusting the tension of the spring for limiting the pressure maintained by said chamber.

In testimony whereof, I have hereunto set my hand at Chicago, Illinois, this 28th day 80 of February, 1923.

CHARLES S. BURTON.
